UNITED STATES PATENT OFFICE.

RICHARD E. SCHLETTNER, OF PHILADELPHIA, PENNSYLVANIA, ASSIGNOR TO SCHLETTNER & ZANDER INC., OF PHILADELPHIA, PENNSYLVANIA, A CORPORATION OF PENNSYLVANIA.

DESIGN FOR HOSIERY.

Application filed December 29, 1923. Serial No. 8,194. Term of patent 7 years.

To all whom it may concern:

Be it known that I, RICHARD E. SCHLETTNER, a citizen of the United States, residing at the city of Philadelphia, county of Philadelphia, and State of Pennsylvania, have invented a new, original, and ornamental Design for Hosiery, of which the following is a specification, reference being had to the accompanying drawing, forming part thereof.

The figure is a perspective view of a pair of hose showing my new design, which appears upon opposite sides of a single stocking.

I claim:

The ornamental design for hosiery as shown.

RICHARD E. SCHLETTNER.
